United States Patent Office

Des. 198,560
Patented July 7, 1964

198,560

BASEBALL GLOVE

Floyd William Kortum, 13006 Atlantic Ave.,
Rockville, Md.

Filed Feb. 13, 1964, Ser. No. 78,615

Term of patent 14 years

(Cl. D3—11)

I claim:

The ornamental design for a baseball glove, as shown.
